UNITED STATES PATENT OFFICE.

DANIEL E. DUNCAN, OF FAR ROCKAWAY, NEW YORK, ASSIGNOR OF ONE-HALF TO
MICHAEL J. McDONNELL, OF FAR ROCKAWAY, NEW YORK.

VEHICLE SPRING.

Application filed May 20, 1924, Serial No. 714,634. Renewed June 2, 1927.

My present invention relates to improvements in springs of the semi-elliptic type and is designed more especially for use in motor vehicles, though not limited to such.

5 The invention aims to provide a construction which will act as a shock absorber on the downward movement of the load, reduce rebound, and, when embodied in the rear springs of an automobile having the Hotchkiss drive, will prevent back lash.

With these objects in view, the invention includes the novel construction hereinafter described and particularly defined by the appended claims, the said invention being illustrated by the accompanying drawing, in which—

The figure shows a side elevation of a spring constructed in accordance therewith.

Referring by reference characters to this drawing, the spring is shown as comprising a plurality of leaves of gradually increasing length, which may be of any desired number and size according to the circumstances under which they are to be used, and which, except as hereinafter specified, may be of the ordinary or any desired construction.

The topmost leaf 1 is provided with eyes 1^a and 1^b at opposite ends to receive the customary shackle bolts (not shown) which eyes are shown conveniently as being formed by banding or curving the spring ends into approximately cylindrical form. Underlying the spring leaf 1 is a second spring leaf 2, which has one end coiled or bent as at 2^a to surround the eye 1^a at the corresponding end of spring leaf, while its other end is bent upwardly as at 2^b to partially surround the corresponding eye 1^b.

Preferably the end 2^b is extended about half way up on the eye portion 1^b and its end is preferably tapered as shown.

The lower spring leaves, 3, 4, 5, and 6, are of the ordinary construction and four are shown merely as an example of any desired number, and an upper short leaf 7 may be used if desired.

It will be readily apparent that my spring leaf 2 may be manufactured as an individual element for incorporation in existing semi-elliptic springs by making it of the proper dimensions, or it can be incorporated in a complete spring by the manufacturer.

It will be understood that where I refer to semi-elliptic springs, I mean to include also the type of springs used in what is known as the "platform" spring.

Having thus described my invention, what I claim is:—

1. A vehicle spring of the semi-elliptic type, comprising a leaf having shackle bolt eyes in its ends, an underlying leaf having one end bent to encircle the shackle bolt eye, the other end bent to partially encircle the other shackle bolt eye, and an overlying leaf terminating short of each shackle bolt eye.

2. A vehicle spring of the semi-elliptic type, comprising a leaf having shackle bolt eyes in its ends, an underlying leaf having one end bent to encircle the shackle bolt eye, the other end bent to partially encircle the other shackle bolt eye and being beveled, and an overlying leaf terminating short of each shackle bolt eye.

In testimony whereof I affix my signature.
DANIEL E. DUNCAN.
